UNITED STATES PATENT OFFICE.

FRANK MAJCHROWICZ, OF CLEVELAND, OHIO.

AUTOMATIC RAILROAD-GATE.

1,391,397.

Specification of Letters Patent. Patented Sept. 20, 1921.

Application filed April 21, 1921. Serial No. 463,201.

To all whom it may concern:

Be it known that I, FRANK MAJCHROWICZ, a citizen of Poland, residing at Cleveland, in the county of Cuyahoga and State 5 of Ohio, have invented certain new and useful Improvements in Automatic Railroad-Gates, of which the following is a specification.

The primary object of the invention is 10 the provision of a gate for railroad crossings whereby accidents are avoided and the highway is rendered safe to the public, my invention providing for the automatic sounding of an alarm as well as the positioning of a gate across the highway adjacent the railroad track upon the approach 15 of a train in either direction, the device being serviceable in connection with either a single or double track road.

20 A further object of the invention is to provide an electrical apparatus designed for opening and closing gates at a railroad crossing and having its operations automatic for taking place when an approaching 25 train is at predetermined distances from the highway crossing.

In carrying out these objects oscillating gates are preferably stationed for positioning transversely and substantially horizontal 30 tal above the highway at opposite sides of the railroad track where the track and highway cross each other, these two gates being rendered simultaneous in their operation, preferably by mechanical connections where- 35 by the automatic operation of one gate controls that of the other gate.

There is provided in connection with the gates a signal lamp mounted upon each gate, the lamps to be lighted only when the gates 40 are in their operative lowered positions or are moving to and from such horizontal positions. One or more audible alarms such as a bell are provided at the crossing which are designed for ringing when a train is 45 approaching in either direction and is a short distance away such as a five-minute run to the crossing, it being observed that such approaching train by closing an electrical circuit causes the alarm bell to sound followed by an almost immediate lowering 50 of the crossing gates to their horizontal transverse arrangement with respect to the highway. It is to be understood that my invention includes such control of alarm 55 bells and signal lamps in conjunction with

the lowering of the pair of highway gates prior to the passing of the train across the highway and the raising or opening of the gates after the train has passed the highway.

By employing my device it is impossible for a train to approach within a predetermined distance of or to cross the highway without lowering the gates and my arrangement further provides that the gate-opening 60 as well as closing mechanism is automatically thrown out of circuit whenever the rails at the crossing are electrically connected, such as by means of a car upon the track, so that accidents are prevented when a car 65 is standing upon the track at a crossing and other trains approaching in either direction can in no possible way close or energize the circuits which under normal conditions effect the opening and closing of the gates.

With these objects of the invention in view and the results to be accomplished by my invention, the mechanism for carrying out the same in an advantageous manner will be now more specifically described.

In the accompanying drawings forming a part of this application like designating characters refer to corresponding parts throughout the several views and these will be referred to in the specification fully setting forth the invention as illustrated in the drawings.

In the drawings,

Fig. 1 is a side elevation of the main frame of the device with parts removed, the 90 gate being shown nearly closed.

Fig. 2 is a top plan view thereof,

Fig. 3 is a rear elevation of the same,

Fig. 4 is an elevational view of a forward portion of the machine taken from the opposite side to that shown in Fig. 1,

Fig. 5 is a horizontal transverse sectional view taken through the device,

Fig. 6 is a horizontal sectional view taken through the rotary switch contacts of the 100 automatic regulator,

Fig. 7 is a diagrammatic view of the mechanism and electrical connections illustrated primarily for a single track line, a second track being illustrated with the wiring indicated by dotted lines electrically connected for operation by the travel of cars in only one direction,

Fig. 8 diagrammatically indicates the electrical connections for the double track 110

railroad therein illustrated as crossing a highway, and

Fig. 9 is an elevational view showing the gate construction.

5 The lay-out of a double and single track railroad equipped with my system of electrically-operated automatic safety devices is broadly illustrated in Figs. 7 and 8 of the drawings while details of different parts of 10 the master machine by which these operations are accomplished are set forth in the remaining figures of the drawings. For sake of convenience in ready reference to the movements of trains upon different sections 15 of the tracks, I have designated the two tracks of a double-track system as track X and track Y in Figs. 7 and 8, the track X however in Fig. 7, being wired for use as a two-way track and the electrical connections 20 for track Y employed as a one-way track are indicated by dotted lines therein. A roadway R is illustrated in Figs. 7 and 8 crossing the tracks X and Y perpendicularly with signal towers or housings 10, 10' positioned adjacent the roadway R and at opposite sides of the roadbed with oscillating 25 gates or arms 11, 11' respectively normally in their open elevated positions and adapted for lowering to their horizontal closed positions for resting upon opposite posts 12 and 30 12' respectively as illustrated by dotted lines in Fig. 8.

The mechanism and electrical connections will be described in connection with the two-way single track X shown in Fig. 7 and the arrangement for a double-track line will then be readily apparent, the one-way tracks of a double-track road being each provided with the operating sections and connections 40 for performing the desired functions during travel only in single and opposite directions upon each track selectively.

The principle upon which the system operates includes normally open circuits adapted for closing by the positioning of a car or train upon insulated sections of track such as B, D, C, U, B', D', C' and U', in Figs. 7 and 8. The presence of a train upon either of the track sections B or B' results in the 45 ringing of an alarm bell S adjacent the roadway R and preferably at the housing 10 or 10', this being accomplished when a car is positioned upon either of the track sections B or B'. The continued travel of the car 50 from track section B, for instance, to and upon an insulated track section D positioned toward the crossing R or from the track section B' to a relatively similarly insulated section D' results in the downward movement 55 of the gates 11 and 11' simultaneously to their horizontal closed positions as illustrated by dotted lines in Fig. 8. The track sections D and D' are at a desirable distance from the road crossing R so that the gates 60 65 11, 11' have sufficient time to entirely lower

for resting upon the posts 12, 12' before the car or train can come dangerously near to the road R. The approaching train has already sounded the alarm bell at the crossing by bridging the rails of the track sections B or B' prior to causing the gates 11 and 11' to lower by bridging the rails of either section D or D'. The car will then pass over the road R upon the track section C or C' with the gates 11, 11' closed, thereby 70 preventing any traffic upon the road R across the tracks X and Y until the train has reached a suitable distance away from the crossing where track sections D and D' are located.

The track sections C and C' of the tracks X and Y respectively are insulated from the remainder of the tracks and are positioned at the point where the tracks cross the road R. An insulated section U of the track X is at the opposite side of the road R from the track section D and the system provides for the opening of the gates 11-11' to their elevated inoperative positions when a train passes upon the section U of the track X when coming from the direction of the road R. In a similar manner, a car upon the insulated track section U' of the track Y closes an electrical circuit whereby the gates 11, 11' which have been lowered by electrically connecting the rails of the track section D', will automatically open to their elevated positions. The sections U and U' are at opposite sides of the road R from the sections D and D', respectively. A train upon the two-way track X, Fig. 7, will only operate to elevate the gates by section U' when they have been previously lowered by a train passing over the section D' in the direction toward the section U' and section U only operates when the gates were lowered by section D. In other words, a car upon the section U cannot open the gates 11, 11' which have been closed by a car upon the section D', nor can a car upon the section U' open the gates which have been previously closed by a car traveling upon the section D.

The alarm bell.

The electrical apparatus for operating the system is preferably inclosed in the housing 10 and is mounted upon a base or other suitable support 13, and includes a top 9 and side plates 14 with forwardly projecting arms 15 in which are journaled the pivoting shaft 16 of one of the gates such as 11, the gate 11 being elevated and lowered by a gear 17 fixed upon the shaft 16 in constant mesh with a gear 18 carried by the shaft 19 journaled through the arms 15 adjacent the forward and inward extensions 20 of the plates 14. A conducting strip 21 is electrically connected with one rail of each of the separate track sections 130

employed in the system such as B, D, U', C, C', D', B' as arranged in the two-way single-track line X in Fig. 7. The bell sections B and B' are connected to the conducting strip 21 from one rail only designated E by circuit wires 22 and 23 respectively while the portions of the same rail E constituting parts of the sections D and D' are electrically connected to the strip 21 by circuit wires 24 and 25 respectively. The portions of the rail sections U and U' are electrically connected to the strip 21 by wires 26 and 27 respectively, and the portion of the rail E in the section C is connected to the strip 21 by a wire 28. A source of electrical supply such as a battery 29 is connected to the strip 21 by a wire 30 and to an operating motor 31 for the gates by a wire 32.

20 The rail F being the companion rail to E in the track such as X has its portions forming parts of the insulated sections B and B' electrically connected to a binding post 33 of a rotary switch mechanism 34 upon the top 25 plate 9 by circuit wires 35 and 36 respectively.

The switch 34 includes a cylindrical body 37 having its axle 38 provided with a lever 39 pivotally connected by a link 40 to a bell 30 crank rocker 41 secured to the shaft 19. The body 37 is formed of insulation and has a conducting plate 42 upon its surface adapted for contact by a spring 43 carried by the binding post 33. A second binding 35 post 44 upon the top of the frame 45 by means of which the switch 34 is mounted upon the top 9, has a spring 46 resiliently contacting the body 37. The operating connections between the body 37 and the 40 shaft 19 are such that the two springs 43 and 46 will be engaged by the plate 42 closing the electrical circuit between the springs when the gate 11 has descended a short distance upon its closing movement 45 and the circuit between said springs will remain closed while the gate 11 is lowered and until it again returns to its upright open position when the contacts 43 and 46 return to their circuit opening position as 50 shown in Fig. 1. The alarm bell S is connected by a wire 47 with the binding post 44, the bell S being of any suitable form and preferably positioned adjacent the housing 10. The bell S is connected by a branch wire 48 with a circuit wire 49, the latter being connected to the wire 32 adjacent the battery 29 and whereby the bell S is at all times electrically connected to the strip 21 through the battery 29.

60 The bridging of the rails E and F in either the insulated section B or B' will therefore close the electrical circuit for the bell S whenever the springs 43 and 46 are in circuit upon the plate 42 and as this occurs when the gate 11 is open and until

it has partially descended it will be seen that the bell S will ring whenever a train enters the sections B, B' with the gate 11 open and will continue to ring while the gate travels downwardly with a portion of 70 the train still remaining in a bell-ringing section of the track. It is obvious that after the train leaves the ringing section of the track, the bell S will cease to operate although upon the return of the gate to open 75 position the bell may again be rung when the installation is upon a two-way single track as the train will pass the second ringing section after traversing the highway R.

The signal light.

80 A similar rotary switch 50 is provided for controlling the electrical circuit to a lamp L mounted upon the outer side of the gate 11, the switch 50 having a cylindrical body 85 51 secured to one end of the shaft 19. A bracket 52 carried by the top 9 has two contact springs 53 and 54 provided with binding posts 55 and 56 respectively. The lamp L is connected by a wire 57 to the binding 90 post 55 while a wire 58 connects the binding post 56 with the strip 21. A branch wire 59 connects the lamp L with the return wire 49, whereby the circuit is completed through the battery 29 and wire 30 95 to the strip 21.

From this it will be evident that the only 100 break in the electrical connection for the lamp L is at the switch 51 and the springs 53 and 54 are electrically connected when they are in contact with a conducting segment 60 of the switch body 51. The segment 60 is brought in position to contact the springs 53 and 54 when the gate 11 is lowered this being accomplished by turning 105 the body 51 with the shaft 19 so that the signal lamp L will be viewable when the gate 11 is closed over the highway R. When the springs 53 and 54 are normally upon the insulated body 51 with the gate 11 open, the 110 electrical circuits will be broken and the lamp L will not be lighted.

The gate lowering mechanism.

115 The mechanism for automatically lowering the gates 11, 11' is brought into engagement by bridging the rails of the insulated sections D and D', the electrical connections of the insulated sections of the rail E with the spring 21 by the wires 24 120 and 25 respectively having been heretofore described. The companion sections of the rail F are connected by wires 61 and 62 respectively with binding posts 63 and 64.

125 The binding post 63 is connected by a wire 65 with the binding post 66 of a circuit changer G. The binding post 64 is connected by a wire 67 with a binding post 68 of the governor G. The binding post 68 has a companion post 69 upon the governor G 130

which is connected by a wire 70 to a binding post 71 upon a suitably positioned distributing plate 72. The binding post 66 has a companion post 73 connected by a wire 74 to a binding post 75 upon the plate 72. The distributing plate 72 is connected by a wire 76 with a safety cut-out overbalanced switch 77, the circuit normally passing through said switch 77 and a wire 78 to the operating 10 motor 31 which is connected to the battery 29 by the wire 32 and to the strip 21 by the wire 30.

The train on track X leaving section B and passing to section D makes electrical 15 connection between the wires 24 and 61, the wire 61, binding post 63 and wire 65 continue the electrical connection from the wire 24 to the binding post 66 of the governor G. The wire 24 is connected to the strip 21 and 20 through the wire 30, battery 29, wire 32, motor 31, wire 78, switch 77, wire 76, distributing plate 72, binding post 75 and wire 74 with the binding post 73 of the circuit 25 changer G. The post 66 has a spring contact 79 and the post 73 a spring contact 80 and these contacts have wiping contact with the conducting segment 81 on the face of a dielectric cylindrical body 82 constituting the rotary member of the circuit changer G 30 and mounted for turning with the transverse shaft 83 of said circuit changer. When the train is upon the section D, the circuit changer G is in its operative position with respect to the electrical connections of 35 sections D in the manner heretofore noted by the wiping contact of the springs 79 and 80 of the conducting segment 81 and from this it will be seen that a circuit is completed from the two rails of the section D 40 through the motor 31 which operates to lower the gates 11 and 11'. The corresponding insulated section D' for a train coming in the opposite direction also effects the lowering of the gates by the similar electrical 45 connections heretofore described, the portion of the track F positioned in section D' being electrically connected to the binding post 68 of the circuit changer G while the portion of the rail E forming a part of the 50 insulated section D' is electrically connected through the motor 31 with the generator binding post 69. The binding post 68 has the spring contact 84 and the post 69 has the spring contact 85 in wiping engagement 55 with the dielectric cylindrical body 82', of the circuit changer G. With the train bridging the rails of section D' and the circuit changer positioned as heretofore described for causing the current to pass to 60 sections D and D', the contacts 84 and 85 will be in engagement with the conducting segment 81' of the body 82' and, thereby, the electrical circuit of the motor 31 being closed, the motor will operate to lower the 65 gates 11, 11' in the same manner as heretofore

described in connection with section D of the track.

The insulated track sections D and D' are preferably in a double track road as X-Y with the section D in the track X and the section D' in the track Y whereby the trains traveling in only one direction upon each track will lower the gates upon entering the sections D or D' whenever approaching the roadway R. The electrical connections for 75 the second track, designated Y in Fig. 7, are indicated by dotted lines; the main lead 62 of the section D' is shown extended to the track Y by dotted lines 62' with the corresponding rail of track Y while the return 80 wire 25 is shown extended by dotted lines 25' to connect the corresponding rail of the track Y. In a similar manner, the bell wire 36 of the section B' is shown extended to track Y by the dotted lines 36' while the return wire for the corresponding rail of the insulated section B' of track Y is indicated by dotted lines 23' as an extension of the return wire 23.

The gate opening mechanism.

Again referring to the two-way single track X in Fig. 7, after the train has passed the bell-ringing section B, the gate closing section D as well as the roadway R, it enters 95 the insulated track section U which has the effect of elevating or opening the gates 11, 11'. One rail of the section U is connected to the strip 21 by the wire 26 as heretofore described whereby the circuit is normally 100 completed through the wire 30, battery 29, wire 32, motor 31, wire 78, switch 77, and wire 76, to the distributing plate 72. The corresponding rail portion of the insulated track section U is connected by a wire 86 105 with a binding post 87 which in turn is connected by wire 88 with a binding post 89, of the circuit changer G. A companion binding post 90 adjacent the post 89, is connected by a wire 91, with the binding post 110 92 of the distributing plate 72. The binding posts 89 and 90 have contact springs 93 and 94 automatically positioned in wiping contact with the conducting segment 81 of the body 82 of the circuit changer G which is 115 automatically positioned in wiping contact with the conducting segment 81' of the body 82' of the circuit changer G which is automatically positioned at such times to complete the electrical circuit as illustrated in 120 Figs. 3 and 6, of the drawings. The electrical circuit being completed by the train upon section U, the motor 31 is energized and its operation causes the gates 11, 11' to open in the manner hereinafter described. 125 The train in this way leaves the gates elevated and the roadway R clear across the track X. The "up" section U' for trains traveling in the opposite direction from that just described, operates in a similar manner. 130

One rail of the section U' is connected by the wire 27 of the strip 21 as heretofore set forth, while said strip 21 is electrically connected through the motor 31 with the distributing plate 72 also specifically noted above. The opposite rail of the section U' is connected by a wire 95 with a binding post 96 which in turn is connected by a wire 97 with a binding post 98 of the circuit changer 10 G. A companion binding post 99 is provided for the binding post 98 upon the circuit changer G electrically connected by a wire 100 with a binding post 101 on the distributing plate 72.

15 The binding posts 98 and 99 are provided with contact springs 102, 103 respectively in contact with the conducting segment 81' of the body 82' of the circuit changer G when the mechanism of the governor is automatically positioned at such times for completing the electrical circuit from the insulated section U' through the motor 31 and whereby the gates 11, 11' are elevated. The employment of the "up" section U' is shown 20 upon track Y in Fig. 7, by a dotted line 27' indicating an extension of the return wire 27 and with the corresponding rail of section U' connected to the extension 95' of the wire 95 also shown by dotted lines. In this 25 manner it will be apparent that after the train has crossed over the roadway R with the gates closed, the passing of the machine over the "up" sections of the track automatically elevates the gates to their 30 open positions.

The safety mechanism.

Insulated sections of tracks C, C' are positioned across the highway R and are designed to accomplish the automatic cutting out of the motor 31 whenever a train is upon the roadway R either in motion or standing still and this prevents the elevating of the gates 11, 11' by another train while the first 45 mentioned train is positioned across the roadway.

One rail of the insulated track section C is connected by the wire 28 to the strip 21 heretofore noted, this strip 21 being electrically connected through the switch 77 with the distributing plate 72. The companion rail of said section C is connected by a wire 104 with one binding post 105 of a controlling device for the switch 77 such as the 50 electro-magnet 106. The opposite binding post 107 of the magnet 106 is connected by a wire 108 with a binding post 109 which in turn is connected by a wire 110 with one side or binding post 111 of the main service switch 77, the opposite binding post 112 of the switch 77 having the motor wire 78 connected thereto.

With a train upon the track section C, the electrical circuit will be completed 65 through the wire 28, strip 21, wire 30, bat-

tery 29, wire 32, motor 31, and wire 78 to the binding post 112 and with the switch 77 normally closed, due to the fact that the switch is overbalanced at the opposite side of its pivot 115 from its armature 113, the current will pass therethrough to the binding post 111 and to the wire 110, post 109 and wire 108 to post 107. As the return circuit from the electromagnet 106 is complete from the post 105 through the wire 104 to the other rail of the track section C upon which the train is positioned, the flow of current will take place through the coils of the electromagnet 106 thereby energizing its core and attracting the armature 113 and oscillating the switch lever 114, upon its pivot 115 and opening the switch 77. The opening of the service switch 77 cuts out the motor 31 and the switch 77 will not close to permit current to pass therethrough to operate any of the "up" or "down" mechanism until the insulated sections C or C' are clear with the rails thereof unbridged. The connections for the automatic cut out mechanism are fully shown for track X in Fig. 7 and 80 in connection with track Y an extension of the lead 104 is shown by dotted lines 104' attached to the portion of rail F' forming a part of the insulated section C'. The section of rail E' in the insulated section C' 85 is shown in circuit with the strip 21 by means of an extension 28' of the return wire 28 as also indicated by dotted lines. The motor 31 upon the base 13 is operatively connected by a train of gears 116 with a 90 power pinion 117 in constant mesh with a driving gear 118 trunnioned upon a post 119 carried by the base 13. A link 120 is pivoted as at 121 eccentrically upon the face of the disk gear 118 with its forward end 95 pivotally connected at 122 to the opposite arm of the bell crank rocker 41 from its attachment with the link 40. The operation of the motor 31 in the uniform direction causes the disk gear 118 to revolve thereby 100 actuating the rocker 41 and oscillating the lever 39 of the switch 34 which is thereby 105 automatically operated to properly position the conducting segment 42 relative of the contact springs 43 and 46 for controlling the 110 bell S.

The bell crank rocker 41 being secured to the shaft 19 causes a partial rotation of the shaft 19 and its gear 18 for turning the gear 17 and moving the gate 11 through an 110 arc of substantially 90°. The turning of the gear 18 from its position shown in Fig. 1, in either direction, rocks the member 41 for elevating the gate 11 and at the same time moves the switch 34 in the direction 115 indicated by the arrow.

The shaft 83 of the governor has a pinion 123 journaled thereon in mesh with a rack 124 pivoted at 125 beneath the shaft 83 and pivotally connected by a link 126 with an 130

arm 127 secured to the shaft 19. A disk 128 concentrically carried by the gear 123 has diametrically opposite lugs or rollers 129 upon its outer face, these rollers 129 being 5 adapted to engage an arm 130 secured to the shaft 83 whenever the rack 124 turns the disk 128 substantially one-half of a revolution by reason of the turning of the shaft 19 when the gate 11 is lowered and elevated.

10 The lowering of the gates positions the governor as herein illustrated with the contact segment 81' engaged by the contact springs 102 and 103 of the opening section of track U' and with the section 81 contacted by the springs 93 and 94 of the elevating track section U. The elevating of the gate 11 by the disk gear 118 is accomplished by the turning of the disk 128 in the direction indicated by the arrow in Fig. 1 of 20 the drawing and whereby the roller 129 engaging the arm 130 rotates the shaft 83 and the switch bodies 82 and 82' until the arm 130' carried by the opposite end of the shaft 83 passes a vertical plane through the axis 25 of the shaft 83 and whereupon the spring 131 suddenly snaps the switch around to its opposite position. This will place the conducting segment 81 in contact with the springs 78 and 80 while the segment 81' will be in contact with the springs 84 and 85 and the mechanism will be in position for responding to the bridging of the rails of either of the track sections D or D' and causing the lowering of the gates 11 and 11'.

30 35 While the two-way single track and its connections are illustrated in Fig. 7 of the drawings which also includes in dotted lines the connections for the second track of a double-track line, Fig. 8 of the drawings is 40 designed to show the regular connections for a double-track system and it will be found to accurately operate with the entire mechanism installed as hereinbefore described.

45 The operation of the invention will be fully understood from the foregoing detailed description of all the operative parts and the electrical connections therefor. The form of the invention herein set forth 50 and described is believed to be the preferable embodiment thereof but it will nevertheless be understood that changes may be made therein without departing from the spirit and scope of the invention.

55 Having described my invention, what I claim as new and desire to secure by Letters Patent is:—

60 1. A railway safety device for highway crossings comprising an oscillating gate adapted for movement across the highway, an electric lamp upon the gate, an electrical bell adjacent the gate, an electric circuit for the lamp adapted for automatic closing when the gate is closed, an insulated track 65 section over which a train is adapted to pass

before reaching the crossing, electrical connections for the rails of said section and said bell, an automatic switch in the bell circuit normally open when the gate is open, a second insulated track section between the 70 bell section of track and the highway, an operating motor for the gate in circuit with said second track section adapted for closing the gate when the circuit between the rails of said second track section is closed by a 75 train positioned thereon, an electrical cut out for the motor, an insulated track section across the highway with the rails thereof electrically connected to the cut out adapted upon closing the circuit between the rails 80 by a train upon the crossing for actuating said cut out whereby the circuits for the opening and closing track sections is rendered inoperative.

2. A railway safety device for highway 85 crossings comprising an oscillating gate adapted for movement across the highway, an electric lamp upon the gate, an electrical bell adjacent the gate, an electric circuit for the lamp adapted for automatic closing 90 when the gate is closed, an insulated track section over which a train is adapted to pass before reaching the crossing, electrical connections for the rails of said section and said bell, an automatic switch in the bell circuit 95 normally open when the gate is open, a second insulated track section between the bell section of track and the highway, an operating motor for the gate in circuit with said second track section adapted for closing 100 the gate when the circuit between the rails of said second track section is closed by a train positioned thereon, a third insulated track section at the opposite side of 105 the crossing from the other insulated sections and operatively connected to said motor whereby the gate is adapted for opening upon the closing of the circuit between the rails of said third section when a train is positioned thereon after passing the highway, an electrical cut out for the motor, an insulated track section across the highway with the rails thereof electrically connected to the cut out adapted upon closing the circuit between the rails by a train upon the 110 crossing for actuating said cut out whereby the circuits for the opening and closing track sections is rendered inoperative.

3. Electric gate mechanism for a single track road, an oscillating gate adjacent the 115 track adapted for positioning transversely of the highway crossing, operating mechanism for the gate, electric actuating means for said mechanism, insulated sections of track at opposite sides of the highway electrically connected to said electric actuating means whereby the gate is automatically lowered when a train approaches the crossing upon one of said track sections selectively in either direction, second insulated sections 120 125 130

between the opposite sides of the highway crossing and the said lowering sections of track, electrical connections between the rails of said second track sections and the electrical operating mechanism whereby the gates are adapted for opening when the electrical circuit is closed between the rails of said section track sections by a train positioned thereon, an electrical cut out for the 10 said electrical operating means, an insulated track section at the crossing electrically connected to said cut out whereby the electrical operating mechanism is rendered inoperative when a train is positioned upon the track 15 at the highway.

4. Electric gate mechanism for a single track road, an oscillating gate adjacent the track adapted for positioning transversely of the highway crossing, operating mechanism 20 for the gate, electric actuating means for said mechanism, insulated sections of track at opposite sides of the highway electrically connected to said electric actuating means whereby the gate is automatically lowered 25 when a train approaches the crossing upon one of said track sections selectively in either direction, second insulated sections between the opposite sides of the highway crossing and the said lowering sections of track, electrical 30 connections between the rails of said second track sections and the electrical operating mechanism whereby the gates are adapted for opening when the electrical circuit is closed between the rails of said 35 second track sections by a train positioned thereon, an electrical cut out for the said electrical operating means, an insulated track section at the crossing electrically connected to said cut out whereby the electric operating

mechanism is rendered inoperative when a 40 train is positioned upon the track at the highway, an automatic circuit changer mechanically connected to the gate operating mechanism and electrically connected in the 45 circuits for the closing and opening track sections whereby the closing of the gate automatically breaks the circuit connections in the circuit changer for the gate closing sections of track and closes the electrical connections in the circuit changer for the opening 50 sections of the track.

5. An electrical safety device for highway crossings of double track lines comprising a 55 gate adjacent the track adapted for oscillating movement across the highway, an operating motor for the gate, insulated track sections for each of the tracks at opposite sides of the highway, electrical connections between the rails of said track sections and the motor adapted for closing an electrical circuit for actuating the motor to close the gate when a train upon either track is approaching the highway and for closing the circuit of the motor for opening the gate 60 after the train has passed upon the track 65 after crossing the highway, insulated sections of each track at the point of crossing the highway, an electrical cut out for the motor operatively connected to the rails of the track sections at the highway crossing 70 whereby a train upon the track at the crossing is adapted for closing the electrical circuit to the cut out and rendering the motor inoperative by trains upon either track of the railroad.

In testimony whereof I affix my signature.

FRANK MAJCHROWICZ.
